UNITED STATES PATENT OFFICE.

GEORGE GLAUDEL, OF LOS ANGELES, CALIFORNIA, ASSIGNOR OF FORTY-TWO AND ONE-HALF PER CENT TO GEORGE L. MITCHELL, OF SANTA MONICA, CALIFORNIA, AND FIFTEEN PER CENT TO HERMAN MILLER, OF SOUTH PASADENA, CALIFORNIA.

GLASS-PLATE HOLDER.

Application filed March 29, 1923. Serial No. 628,678.

To all whom it may concern:

Be it known that I, GEORGE GLAUDEL, a citizen of France, residing at Los Angeles, in the county of Los Angeles and State of California, have invented new and useful Improvements in Glass-Plate Holders, of which the following is a specification.

This invention relates to jigs and fixtures, and has for its object to provide a glass plate holder to facilitate the grinding of edges of plates of glass to remove their sharpness at the corners.

Another object is to provide a glass plate holder of simple construction, and which enables the rapid assembly or stacking of a number of superposed plates with edges to be ground set up in a common plane. An object is to provide means whereby plates may be stacked in slightly spaced position to permit the entry of a sand blast around corners of the stack of plates that are to be ground off by the sand blast. Another object is to provide means for yieldingly clamping the plates in stacked position, and which means is adapted to be quickly thrown into and from effective position for conservation of time and labor in use of the jig.

Other objects and advantages will be made manifest in the following specification of an embodiment of the invention illustrated in the accompanying drawings, wherein—

Figure 1 is a plan of the jig showing a stack of plates, the holder cover being removed.

Fig. 2 is a vertical, longitudinal section of the jig.

Fig. 3 is a vertical, transverse section of the jig in open position.

Fig. 4 is an end elevation, parts broken away, the jig being closed.

The present invention consists of a holder having a plane bottom 2 and parallel, perpendicular end walls 3, the front and back of the holder being open to permit ready insertion and removal of pieces or plates of glass G, certain corners of which are to be ground off by a sand blast. The end walls 3 are provided with channels 4 in their inner faces, and into these channels is adapted to be slipped a guide plate 5, having a plane inner face against which the superposed pieces of glass G may be thrust so as to bring the contiguous faces into a common plane along the guide plate 5.

As each of the plates are superposed, they are preferably spaced a suitable distance, and this is accomplished by the insertion of a spacing sheet 6, which may be of paper or any other suitable material that may be prepared and used at low expense and readily renewed when unduly worn. The front edge of each of the spacing sheets 6 may be recessed at 6^a for a suitable portion of the length and thus leave shoulders 6^b, which can be thrust against the guide plate 5 for proper positioning.

For effective and quick utilization of the jig in the sand blasting of the plate edges, these are preferably uniformly stacked so that their ends will be in an approximately common plane, and for this purpose the end walls 3 of the holder are provided with inwardly extending jack screws 7, the inner ends of which are turnably mounted in end blocks 8, adjustable inwardly from the walls 3 so as to form end guides for the glass plates.

After a stack of pieces of glass has been built up in the holder, the guide plate 5 is removed from its channels 4 and a pressure device is lowered down into clamping position upon the topmost piece of glass. Such a clamping means includes a pressure-head 10 of somewhat less dimensions than the glass pieces being operated upon. This pressure-head is provided with one or more pins 11, surrounded by compressed springs 12, and which pins pass through a swinging leaf 13 which is hingedly connected at 14 to the rear corners of the end walls 3, so that the leaf 13 can be thrown upwardly to an open position, clearly shown in Figure 3, in which it is maintained by abutment shoulders 15, associated with the hinge 14.

The pressure head 10 is attached to the top forming leaf 13 by means of a connecting rod 16 passing through the leaf and being attached to a lever 17, which is pivoted at 13^a on a bracket provided on the leaf 13. The holder is provided with upwardly projecting pins or stops 8^a down against which the leaf 13 may be turned.

The lever 17 is provided with a ratchet pawl 18, and this is adapted to lock the lever 17 in a position holding the pressure-head 10 drawn toward the leaf 13, and thus compressing the springs 12 and a spring 12^a which surrounds the connecting rod 16. The

pawl 18 is engageable with the shank 19 of a handle 20, fixedly provided on the leaf 13, and which shank has a ratchet shoulder 19^a over which the pawl 18 clicks when the lever 17 is gripped and pulled up toward the handle 20.

After the stack of glass pieces has been built up, the handle 20 of the covering leaf 13 is grasped and pulled down to bring the pressure-head 10 down upon the plates. The head yields as it engages the plate as to the leaf 13, and to prevent this from being sprung back, a fastening hook 21 is pivotally mounted at 22 on each of the end walls 3 of the holder; these hooks being adapted to engage lugs 23 provided to receive the same on the ends of the leaf 13. As the head is pressed down upon the stack of glass pieces, the pawl 18 becomes disengaged from the handle shoulder 19^a and, after the leaf 13 has been hooked in position, the springs 12—12^a firmly hold the glass plates in their stack with the front aligned edges exposed to be subjected to the sand blast from any suitable instrument. The action of the sand blast is to round off the front spaced corners of the stack of glass pieces.

After the glass pieces have been thus sand blasted at their front edges, the operator grasps the handles 17 and 20 and draws the handle 17 toward the handle 20, thus lifting the pressure-head from the stack of glass pieces, and latches the retracted head by the pawl 18. Then the hooks 21 are tripped and the leaf with the attached pressure-head thrown open.

Further embodiments, modifications and variations may be resorted to within the principle of the invention.

What is claimed is:

1. In a jig for lining up and holding pieces of plate glass in a stack, a holder having a bottom upon which the pieces are stacked one above the other, end guide means for the ends of the pieces and a removable front guide plate against which the pieces are positioned in alignment in the stack, and means for clamping the stack of pieces whereby to hold the same when the front guide plate has been removed to expose the aligned edges of the plates to be sand blasted.

2. In a jig for lining up and holding pieces of plate glass in a stack, a holder having a bottom upon which the pieces are stacked one above the other, end guide means for the ends of the pieces and a removable front guide plate against which the pieces are positioned in alignment in the stack, and means for clamping the stack of pieces whereby to hold the same when the front guide plate has been removed to expose the aligned edges of the plates to be sand blasted, the holder having guide portions in

which the guide plate is detachably mounted.

3. In a jig for lining up and holding pieces of plate glass in a stack, a holder having a bottom upon which the pieces are stacked one above the other, end guide means for the ends of the pieces and a removable front guide plate against which the pieces are positioned in alignment in the stack, and yieldable means for clamping the stack of pieces whereby to hold the same when the front guide plate has been removed to expose the aligned edges of the plates to be sand blasted.

4. In a jig for lining up and holding pieces of plate glass in a stack, a holder having a bottom upon which the pieces are stacked one above the other, end guide means for the ends of the pieces and a removable front guide plate against which the pieces are positioned in alignment in the stack, and means for clamping the stack of pieces whereby to hold the same when the front guide plate has been removed to expose the aligned edges of the plates to be sand blasted, said means including a foldable top leaf to which is yieldably attached a pressure-head adapted to be forced down upon the stacked pieces.

5. In a jig for lining up and holding pieces of plate glass in a stack, a holder having a bottom upon which the pieces are stacked one above the other, end guide means for the ends of the pieces and a removable front guide plate against which the pieces are positioned in alignment in the stack, means for clamping the stack of pieces whereby to hold the same when the front guide plate has been removed to expose the aligned edges of the plates to be sand blasted, said means including a foldable top leaf to which is yieldably attached a pressure-head adapted to be forced down upon the stacked pieces.

6. In a jig for lining up and holding pieces of plate glass in a stack, a holder having a bottom upon which the pieces are stacked one above the other, end guide means for the ends of the pieces and a removable front guide plate against which the pieces are positioned in alignment in the stack, means for clamping the stack of pieces whereby to hold the same when the front guide plate has been removed to expose the aligned edges of the plates to be sand blasted, said means including a foldable top leaf to which is yieldably attached a pressure-head adapted to be forced down upon the stacked pieces, and a latch means for holding the pressure head in retracted position on the withdrawn leaf.

7. In a jig for lining up and holding pieces of plate glass in a stack, a holder

- having a bottom upon which the pieces are stacked one above the other, end guide means for the ends of the pieces and a removable front guide plate against which the front guide plate has been removed to expose the aligned edges of the plates to be sand blasted, said end guide means including adjustable end blocks.
- 5 the pieces are positioned in alignment in the stack, and means for clamping the stack of pieces whereby to hold the same when

In testimony whereof I have signed my name to this specification.

GEORGE GLAUDEL.
